CLAIM

The ornamental design for a bracket with speakers for television receiver as shown and described.

DESCRIPTION

1. Bracket with speakers for television receiver
1.1 is a front, top and right side perspective view of a bracket with speakers for television receiver showing our new design;

1.2 is a rear, top and right side perspective view thereof;

1.3 is a front elevation view thereof;

1.4 is a rear elevation view thereof;

1.5 is a left side elevation view thereof, the right side elevation view being a mirrored image thereof;

1.6 is a top plan view thereof, the bottom plan view being a mirrored image thereof; and

1.7 is another front, top and right side perspective view thereof, shown in an environment of use.

The broken lines shown in Figures 1.1-1.4 illustrate portions of the bracket with speakers for television receiver that form no part of the claimed design. The broken lines shown in Figure 1.7 illustrate environment that forms no part of the
